J. E. TORBERT

COUNTER GUARD

Filed March 16, 1923

Patented Jan. 22, 1924.

1,481,762

UNITED STATES PATENT OFFICE.

JAMES E. TORBERT, OF FAUNSDALE, ALABAMA.

COUNTER GUARD.

Application filed March 16, 1923. Serial No. 625,495.

To all whom it may concern:

Be it known that I, JAMES E. TORBERT, a citizen of the United States, residing at Faunsdale, in the county of Marengo and

5 State of Alabama, have invented certain new and useful Improvements in a Counter Guard, of which the following is a specification.

10 My invention relates to devices for protecting food, merchandise and other wares, when displayed on tables, counters and the like. The primary object is the provision of an improved and efficient guard adapted to be detachably secured over the top of a 15 table, counter or the like.

Another object of the invention is to provide a device of this character embodying a screened cover provided with doors so that access may be had to the interior.

20 With these general objects in view, and such others as will be apparent from the description, my invention resides in the novel construction, combination, and arrangement of parts hereinafter described and claimed, 25 and illustrated in the accompanying drawings, of which—

Figure 1 is an elevation of an applied guard,

Figure 2 a fragmentary bottom plan view, 30 Figure 3 a vertical section on line 3—3 of Fig. 1,

Figure 4 a detail view of the clamps employed,

Figure 5 a horizontal section on line 5—5 35 of Fig. 1,

Figure 6 a fragmentary bottom plan at one corner.

The guard comprises a substantially rectangular upright triangular frame covered 40 with foraminous material and adapted to rest over the top of a table or counter 1, with the sides of the frame extending below the table edges as shown in Figure 3. In this preferred form, the device is constructed of 45 metal frame strips and wire screening, but any suitable material may be used.

In detail, the guard consists of a frame having a bottom formed of longitudinal, 50 relatively wide, flat metal side strips 2 and 3 and end strips 4 and 5 slightly spaced from a similar inner section formed of the side strips 6 and 7 and end strips 8 and 9. At each end of the frame are triangular uprights formed of angle metal strips 10 and 55 11, and midway of the frame is a central triangular brace consisting of a flat metal

strip 12. The end uprights and central brace are connected across the top of the frame by an angle metal ridgepiece 13 and at each end and side of the frame, the lower ends of the 60 uprights 10 and 11 and brace 12 extend downwardly between the respective side and end strips 2, 3, 4, 5, 6, 7, 8 and 9. A wire screen covering 14 is secured between the uprights and braces just described and an inner section consisting of similar end uprights 15 and central brace 16, the lower ends of which extend downwardly between the inner and outer sections of the frame bottom, and are secured by means of rivets 65 70 or other suitable fastening elements 17 passed through the various members described.

Midway of one side wall extends a longitudinal brace formed of inner and outer flat 75 metal strips 18 and 19, at which point the screen cover 14 terminates and is secured between the two strips. This construction provides an opening in the lower half of the side wall, which is closed by screen doors 20, equipped with handles 21. Secured on the outer face of the strip 12 is a double guideway 22 to receive the adjacent ends of the doors 20, which slide at their opposite ends in similar guideways 23 mounted on the end 80 85 uprights.

As illustrated particularly in Figures 2 and 6, the strips 2, 3, 4, 5, 6, 7, 8, and 9, are crimped or bulged at the corners of the frame to provide for the reception of the 90 lower ends of the uprights, and to present a reinforce at the corners.

Suitable clamping means is provided for securing the guard to the table or counter top, and consists of a plurality of oppositely 95 disposed metal plates 24 provided at one end with lateral flanges 25 and at their opposite end with inwardly extending slots 26 whereby the plates are slidable over bolt stems 27 passed through the adjacent frame strips 100 and slots. Nuts 28 are carried on the bolt stems for clamping the plates in the desired position on tightening thereof. The flanges 25 engage the table or counter top.

In use, the cover is placed over the top 105 of a table or counter holding the articles to be displayed, and the clamps 24 adjusted to engage the top thereof by means of the nuts.

While in this preferred form as illustrated and described, I have stated the use of certain details and materials entering into the construction and operation of the device, I 110

desire it to be understood that I do not intend that the invention shall be limited to same, but that any such may be used, and any modifications made as will fall within 5 the scope of the invention as claimed.

I claim:—

1. A device of the character described, comprising a frame formed of similarly arranged inner and outer sections, a screen 10 cover over said frame and secured between said sections, portions of said sections being disposed in slightly spaced relation, plates slideable between said portions of the sections, clamping ears carried by said 15 plates, and means passed through said sections and plates for adjustably securing said clamping ears to clamp said frame on a table top.

2. A device of the character described, comprising a substantially rectangular frame having relatively wide vertically disposed bottom side and end members, adapted to engage over a table top, triangular 20 end uprights in the frame, a ridgepiece connecting said uprights, a screened cover over 25 said frame, bolt stems carried by said side and end members, vertically slotted plates slideable over said stems, lateral ears carried by said plates and projecting inwardly of the frame to engage a table top, and nuts 30 on said stems for clamping said plates to the side and end members to secure said frame on a table top.

In testimony whereof I affix my signature.

JAMES E. TORBERT.
